[57] CLAIM

The ornamental design for a web drying section, as shown and described.

DESCRIPTION

FIG. 1 is a front elevational view of a web drying section showing my new design;

FIG. 2 is a bottom plan view thereof;

FIG. 3 is a top plan view thereof;

FIG. 4 is a front elevational view of a second embodiment of the design shown in FIG. 1;

FIG. 5 is a top plan view thereof;

FIG. 6 is a bottom plan view thereof;

FIG. 7 is a left side elevational view of the first embodiment;

FIG. 8 is a right side elevational view thereof;

FIG. 9 is a rear elevational view thereof;

FIG. 10 is a perspective view thereof;

FIG. 11 is a left side elevational view of the second embodiment;

FIG. 12 is a right side elevational view thereof;

FIG. 13 is a rear elevational view thereof; and

FIG. 14 is a perspective view thereof.

In a papermachine dryer section, a plurality of dryer rolls at equal elevation are provided for drying a first side of a web, followed by a plurality of dryer rolls, each at a second elevation, for drying a second side of the web.
